UNITED STATES PATENT OFFICE.

CHARLES L. RAYFIELD, OF CHICAGO, ILLINOIS, ASSIGNOR TO FINDEISEN & KROPP MANUFACTURING COMPANY, OF CHICAGO, ILLINOIS, A CORPORATION OF ILLINOIS.

CARBURETER.

1,335,389.

Specification of Letters Patent. Patented Mar. 30, 1920.

Application filed September 15, 1918. Serial No. 789,730.

To all whom it may concern:

Be it known that I, CHARLES L. RAYFIELD, a citizen of the United States, and a resident of the city of Chicago, in the county 5 of Cook and State of Illinois, have invented certain new and useful Improvements in Carbureters; and I do hereby declare that the following is a full, clear, and exact description of the same, reference being had to 10 the accompanying drawings, and to the numerals of reference marked thereon, which form a part of this specification.

My invention relates to carbureters and has for its object to provide certain improvements in the construction and operation of the same, as will be hereinafter more definitely pointed out and claimed, reference being had to the accompanying drawings in which—

20 Figure 1 is a central vertical section taken longitudinally of a carbureter and with parts shown in elevation.

Fig. 2 is a top plan view of the same.

Fig. 3 is a section on line 3—3 of Fig. 1, 25 with parts in elevation.

Fig. 4 is a section taken on line 4—4 of Fig. 2, with parts in elevation.

Fig. 5 is a fragmentary elevation of a cam actuating means for opening the supply valve.

Fig. 6 is an enlarged section taken on line 6—6 of Fig. 2, with parts in elevation.

Fig. 7 is a section taken on line 7—7 of Fig. 2, with parts in elevation.

35 Fig. 8 is a top plan view of the conical valve element.

Fig. 9 is an enlarged fragmentary detail of the adjustable mounting of the needle valve closure.

40 As shown in the drawings:

The carbureter comprises an integral casting, affording a float feed chamber 1, an air inlet chamber 2, a mixing chamber 3, and an outlet chamber 4. Air is admitted to 45 the chambers 2, and 3, by means of an air inlet pipe 5, which, at a point opposite said chamber 3, has secured in an apertured lug 6, formed on the outside thereof, a fixed rod 7, on which is slidably mounted a puppet valve 8, held closed by a helical spring 9, bearing against a nut 10, on said rod 7. As

it is sometimes desirable to heat all the air entering the carbureter, said inlet passage 5, affords a convenient means for introducing the heated air to the several inlets, and with this exception has nothing whatever to do with the functions of carburation and could readily be dispensed with. The air intake pipe 5, communicates with said chamber 3, through said valve 8, by means of an auxiliary passage 11, so that when the draft exerted by the engine becomes sufficiently strong as to require a greater air supply than that furnished through said chamber 2, the spring resisted valve 8, opens to augment the flow of air.

Threaded into the lower end of the float feed chamber 1, is a nut 12, apertured and internally threaded to receive a fuel supply pipe 13, and at its upper end affording a valve seat for a needle valve 14, which is rigidly engaged in a double flanged element 15, slidably mounted in a cover 16, of the float feed chamber. A head 17, is provided on the upper extremity of said needle valve, and pivotally mounted upon one side of a small casing 18, is a crank 19, adapted to engage beneath said head 17, to lift the needle valve, though normally impelled out of contact therewith by means of a spring pressed 80 against 20.

For the purpose of automatically operating said needle valve to maintain a constant level of fuel in said float feed chamber a pair of downwardly projecting lugs 21, are 8 provided on the under side of said cover 16, and journaled therein are levers 22, the inner ends thereof rounded and adapted to engage between the flanges on said element 15, and with the outer ends thereof weighted 90 with the enlarged ball members 23, which normally rest on the upper surface of a float 24. The float 24, is slidably mounted on said needle valve, so that an upward movement of said float causes a corresponding 9 downward movement of the needle valve to close the same, and with a lowering of the float, due to a drop in the level of the fluid within the float feed chamber, the weighted ball members 23, serve to open the needle 1 valve to admit fuel into the chamber.

A combined fuel supply and dash pot

chamber 25, is formed integrally in the bottom of said chamber 2, and communicates with said float feed chamber 1, by means of a passage 25^a. Threaded in the upper wall 5 of said chamber 25, is an upright tubular member 26, having upper and intermediate heads 27, and 27^a, threaded thereon, thus permitting adjustment of the two to vary the distance therebetween. The portion of 10 said member 26, between the heads 27 and 27^a, is provided with large and relatively long slots 26^a, for a purpose hereinafter described. Slidably mounted in said tubular element 26, is another tubular member 28, 15 having a piston 29, at the lower end thereof fitting in said chamber 25, and with a plurality of apertures 28^a, positioned above said piston. Secured on said tubular element 28, at the upper end thereof is a hollow double 20 conical member designated by the reference numerals 30, and 31, respectively, the upper portion 30, adapted to seat on the tapered edge of the casing between the chambers 3, and 4, and the lower member 31 25 adapted to fit within the annular flange 31^a provided between the chambers 2 and 3.

The upper portion 30, of said valve member is open, as shown in Fig. 8, and the lower portion is provided with a plurality 30 of apertures 32, and said stem element 28, is provided with apertures 33, which in all 35 positions of said stem register with said slots 26^a, to permit a flow of hydro-carbon therethrough. The lower end of said element 28, is adapted, when in lowered position, to rest upon a relatively long needle valve closure element 34, which is mounted on a lever 35, by means of a ball and socket joint, said element 34, being held upwardly 40 in position by a pivoted leaf spring 36, secured on said lever 35. The taper of said closure element 34, is so slight that the area of opening effected by an elevation of the tubular element 28 therefrom is very much 45 less than that of the normally open inlet ports 28^a. The lower end of said chamber 25, is closed by means of a nut 37, internally threaded to receive a drain pipe 38, which may be fitted with a pet cock, though not 50 shown, for the purpose of draining the same when desired. Said lever 35, is suitably pivoted on a pin 39, threaded into a horizontal tubular extension 40, of the carbureter which communicates with said 55 chamber 25, the outer end of said tubular extension being closed by means of a threaded plug 41.

Also integrally formed on a central portion 60 of the carbureter and communicating with said horizontal tubular extension 40, is a cylindrical element 42, having an actuating piston 43, mounted on a rod 44, slideable therein, said piston 43, normally resting on the outer end of said lever 35. A 65 notched head 45, is rigidly secured on the

upper end of said stem 44, and is adapted to be engaged by a spring pressed detent 46, which is mounted in a rotatable lever 47.

An apertured plug 48, is secured in said cylindrical element 42, by means of a screw 70 42^a, engaging in a peripheral groove 48^a, in said plug. The plug 48, receives said stem 44, therethrough, and is notched on opposite sides to receive cam elements 50, of similar shape formed on the lower portion of said 75 lever 47. Accordingly, when said lever 47, is actuated the projection 50, and the notch are thrown out of engagement, causing an elevation of said lever 47, with a consequent raising of said piston 43, and release of 80 said lever 35, whereupon the needle valve closure 34, drops downwardly away from the tubular element 28, permitting a flow of hydro-carbon therethrough.

This is particularly desirable just at the 85 starting of an engine, as a quantity of fuel will thereby be drawn upwardly through said tubular element 28, and sprayed within said conical member 30, which, being in closed position will permit a very rich mix- 90 ture to be drawn upwardly around the edge of the head 27, and through the upper end of said member 30, and thence to the manifold of the engine. A sleeve 49, loosely 95 engages around the cam engaging portions of the elements 47, and 48.

Auxiliary means operating independently of the sleeve valve is also provided for initially priming the manifold of the engine at the moment of starting the same. 100

This comprises a tubular element 53, formed on one side of said float chamber 1, and communicating therewith by means of a passage 54. A ball 55, lies within said tubular member 53, to normally close said 105 passage 54, from the float chamber, and a piston 56, normally rests thereon to maintain said ball in closed position. A lateral extension 57, having a passage 58, therein, communicating with said tubular element 110 53, is formed on one side of said tubular element 53, said extension 57, having an enlarged chamber 59, therein, communicating with said passage 58, though normally closed therefrom by means of a ball 60. 115

Threaded in the upper end of said extension 57, is a union 61, adapted to receive a supply pipe engaged thereto, though not shown, and led directly to the manifold of the engine for introduction of fuel thereto 120 without passing through the various mechanisms of the carbureter. Said piston valve 56, as shown in Fig. 7, in its lower position also serves to close the passage 58, so that draft exerted by the engine can have no 125 effect upon the ball 55, to raise the same and permit a flow of hydro-carbon unless said piston valve 56, is raised. For the purpose of raising said piston 56, a stem 56^a, is rigidly connected thereto and extends 130

upwardly through the cover 16, of said float feed chamber into an auxiliary casing 62, and is there provided with a head 63, adapted to be engaged on its under surface by means of an actuating lever 64, any suitable actuating mechanism for the operator, of course, being connected thereto.

As shown in the upper portion of the carbureter above the outlet chamber 4, a customary throttle or outlet valve 65, is provided which controls the flow of mixture from the carbureter. An attaching flange 66, extends outwardly along the upper portion of the carbureter affording a means of attachment therefor to a manifold of an engine, and at the points indicated by the reference numerals 67, the carbureter is shown as water jacketed to keep the device warm if desired.

At the entrance to said air inlet chamber 2, an integral extension 68, is formed in the lower portion of the carbureter which communicates with said dash pot chamber 25, by means of a passage 69, and communicating in said extension 68, and extending upwardly into said auxiliary air inlet passage 11, is a pipe or nozzle 70, adapted to introduce a spray of hydro-carbon into the auxiliary air passage 11, and serving also as a means for supplying an extra amount of fuel when the valve 8 is opened by suction.

The operation is as follows:

It is apparent from the construction that the carbureter is provided with two air ports, one of which is more or less open at all times when the engine is running, and the other normally closed but serving to introduce an auxiliary air supply when its valve 8 is opened under increased suction of the engine. Between the air inlet and mixing chambers of the carbureter the double conical valve 30-31, is provided, the upper member 30, seating upon the tapered portion of the casing between chambers 3, and 4, and the lower conical portion 31, serving to close communication between chambers 2, and 3, although of course a flow of air may take place upwardly from said chamber 2, through said conical valve member, and likewise around the exterior thereof when the same is raised.

For the purpose of preventing an unrestricted flow of air through the conical valves 30-31 when the same is in the lower position, a head 27^a, is mounted to close communication between the interiors of said respective conical valve elements 30, and 31. However, when the engine is running the draft upon the carbureter will cause an elevation of said conical valve member 30-31, thus permitting a flow of air both around the exterior thereof and through the interior of course mixing with the hydro-carbon which flows upwardly through said tubular element 28, and outwardly through said

apertures 33, and through the opening in the upper end thereof, and, owing to the fact that said tubular element 28, is connected to said valve member 30-31, an elevation of said valve will likewise cause an elevation of said element 28, away from the closure element 34, thus permitting a greater quantity of hydro-carbon to flow therethrough.

Thus the valve member 30-31, is the moving element of two air valves afforded by co-action of said member with the seat 30^a, and the head 27^a and flange 31^a. The head 27, is never completely closed, whereas the valve seat 30^a, is normally closed. The valves of which the elements 27^a and 31^a, form a part, constitute the main air inlet system, and either may have its co-operating parts loosely fitted, so as to permit some air to flow past it when valve 30^a, is closed, while the other is a closer fit and completely cuts off the air supply through its respective port except when suction is sufficient to open it.

The action of the piston 29, in the dash pot chamber upon the double hollow valve member 30-31, to which it is connected, is a retarding action, serving to retard the movement of said member 30-31, in its movements as differentiated from the action of a resisting spring which is sometimes used in carbureter structures. That is to say, to retard the movements of the valve member 30-31, is to delay the movements thereof, but not necessarily restrict the movements except as to the matter of the period of time involved. The time involved may be lengthened due to the retarding action of the piston in the dash pot, but the piston in the dash pot does not prevent the full movement taking place. On the other hand, an opposing or resisting spring does not retard the movement, but does provide a balancing force, and thus determines the point where a given force will meet an equal opposing force and thus set a limit to the movements of the member with which the spring is associated.

The retarding element does not react to move the valve, but resists its movement. It tends to maintain a mechanical status. The whole dash pot system is so constructed that it serves the double purpose of retarding the opening of the air valve and pumping fuel under pressure through the fuel supply system.

Acting in its function as a retarding means, when the throttle is suddenly opened the air inlet opening lags behind the mixture outlet opening and the strong suction existing above the throttle when it is partially closed is suddenly transferred to the interior of the carbureter when the throttle is thus opened and is not immediately relieved by a corresponding opening of the

inlet valve, so that during the period occupied in accelerating the motor, a suction stronger than normal for the various speeds attained is effective on the jets.

5 As already mentioned, one of the principal features of this type of carburetor is the introduction of fuel into the proper chambers by mechanical means augmented, of course, by the suction or draft of the engine, 10 the actual mechanical transference of fuel being effected by the piston in the dash pot connected to the conical air valve of the device.

Assuming the valve 30—31 to be in closed 15 position, if the throttle is opened and the engine turned over said valve 30—31, will immediately tend to jump upwardly with a sudden movement, but, of course, retarded by the piston in the dash pot, whereupon the 20 fuel contained in the dash pot chamber 25, above the piston 29, will be placed under pressure thus causing the same to flow into the tubular element 28, through the apertures 28^a, and outwardly through the apertures 33. The movement of the piston causes 25 the fuel to be sprayed outwardly with considerable force, and the pressure will also be transmitted to the chamber 68, thus causing the fuel to be also sprayed through said 30 auxiliary nozzle 70.

The initial heavy charge of fuel introduced into the proper chambers in this particular type of carburetor is particularly well adapted to permit an engine to pick up 35 or accelerate in a short space of time. An important test determining the sensitiveness or responsive action of the carburetor is to open the throttle wide when the engine is running at low speed in order to determine 40 the shortest time in which the engine will pick up to its highest speed under a certain load.

It has been found in this particular type 45 of carburetor that the initial movement of the valve member 30—31 causes the fuel to be actually pumped under pressure and sprayed into the proper chambers, with considerable force so that with an instant opening of the throttle valve the carburetor responds and does not lag, for a period of 50 from five to ten seconds as has been found heretofore, until the automatic mechanisms of the carburetor adapt themselves to the change in conditions.

55 Of course, the pumping or mechanical action which introduces the fuel is only momentary, but is sufficient to cause the engine to respond to an instant opening of the throttle, thus allowing the other mechanisms 60 of the carburetor to adapt themselves to the new conditions, a sufficient amount of fuel having been supplied and in quantities to run the engine during the interval of time required for the carburetor mechanisms to readjust themselves.

Thus the quantity of hydro-carbon introduced into the carburetor is governed by the draft of the engine. When the load upon the engine becomes very great and the draft increases, the automatic valve 8, opens to 70 supply sufficient air to provide for the increased flow of fuel which takes place through said nozzle 70.

The threaded connection between the stem of said notched head 45, and the lever 47, 75 permits an adjustment to be effected to regulate the opening and closing of said tubular element 28, by said closure 34, to suit the conditions. Likewise the adjustment of said automatic valve 8, may be changed by suitably manipulating the nut 10, on the inner end of said stem 7. Other adjustments of the various parts will be evident from the description so that it is readily apparent that the carburetor is adapted to practically any 80 field of operation or use requiring only a preliminary adjustment therefor.

I am aware that various details of construction may be varied through a wide range without departing from the principles 90 of this invention. I therefore do not pur- pose limiting the patent granted otherwise than necessitated by the prior art.

I claim as my invention:

1. In a device of the class described, a 95 float feed chamber, a mixing chamber, a fuel inlet leading from said float chamber to said mixing chamber, an outlet chamber, an inlet chamber for the mixing chamber, an auxiliary air valve opening into said 100 mixing chamber, and a double valve member intermediate said inlet chamber and said outlet chamber adapted to open proportionately with the draft exerted by the engine.

2. In a device of the class described a 105 float feed chamber, an outlet chamber, an air inlet, a double valve interposed between said outlet chamber and said inlet, a tubular valve stem connected to said valve and adapted to receive a supply of fuel from said 110 float feed chamber, and an adjustable closure for said tubular stem adapted to permit a variation in the opening thereof when said tubular member is lifted to permit a flow of hydro-carbon therethrough. 115

3. In a device of the class described a double hollow valve, a tubular valve stem connected thereto adapted to move therewith, a piston connected thereto adapted to move therewith, and means introducing hydrocarbon through said tubular valve stem into the interior of said valve. 120

4. In a device of the class described, a float feed chamber, an outlet chamber, an air inlet, a hollow double conical valve member interposed between said outlet chamber and said inlet, a tubular valve member in connection with said float chamber connected to said valve chamber and adapted to move therewith, a closure fixed in adjusted 125 130

position at the lower end of said device adjusted to close said tubular member in its lowest position, and means for manually depressing said closure to permit a flow of 5 hydro-carbon through said tubular member.

5. In a device of the class described a carbureter, a float feed chamber thereon, an outlet chamber therein, a normally open air inlet, an auxiliary normally closed air inlet, 10 a double hollow conical puppet valve mounted in said carbureter between the outlet chamber and said normally open air inlet, a valve stem on said conical valve, and means introducing hydro-carbon fuel 15 through said valve stem into said hollow conical valve.

6. In a device of the class described an inlet and outlet therefor, a hollow double valve member interposed therebetween, and 20 means for introducing hydro-carbon fuel into the chamber formed within said hollow valve member.

7. In a device of the class described, a float feed chamber, an air inlet chamber, an 25 outlet chamber, a mixing chamber intermediate said air inlet chamber and said outlet chamber, a double hollow valve member closing the respective openings between said respective outlet and inlet chambers, and 30 said mixing chamber, and means introducing hydro-carbon fuel from said float chamber into said mixing chamber through said hollow valve member.

8. In a carbureter a float feed chamber, 35 an outlet chamber, an air inlet for said carbureter, a gravity acting normally closed double valve between said outlet chamber and said air inlet, a hollow valve stem for said valve, a piston on the end thereof, a 40 dash pot adapted to receive hydro-carbon fuel from said float feed chamber and to receive the lower end and piston of said hollow stem therein, and a valve closure in said dash pot adapted to regulate the quantity of fuel drawn upwardly through 45 said hollow valve stem.

9. In a device of the class described a carbureter, a float feed chamber therefor, a mixing chamber, an air inlet, a dash pot in the lower end of said carbureter adapted 50 to receive hydro-carbon fuel from and communicating with said float feed chamber, a tubular extension threaded on said dash pot, a hollow valve stem slideable through 55 said tubular extension and projecting into said hydro-carbon dash pot, a piston on the end of said stem, a double valve member on the upper end of said stem adapted to move said stem when said valve is moved, and a 60 closure adjustably mounted in said dash pot chamber adapted to regulate the opening into said hollow valve stem to permit a flow of hydro-carbon fuel therethrough.

10. In a device of the class described a 65 float feed chamber, an outlet chamber, an

air inlet, a suction operated double valve member mounted intermediate said outlet chamber and said air inlet, a hollow valve stem therefor, means introducing fuel through said hollow valve stem, and an 70 auxiliary passage through double valve to permit flow of a hydro-carbon mixture into the outlet chamber when said double valve member is closed.

11. In a device of the class described a 75 float feed chamber, a dash pot chamber, in communication therewith, an auxiliary hydro-carbon nozzle, passages connecting said dash pot chamber and said hydro-carbon nozzle one to another to permit a flow 80 of hydro-carbon fuel thereinto, an automatically operating double valve member, a hollow valve stem thereon projecting into said dash pot chamber, a piston thereon, and a closure adapted to project into the 85 lower end of said hollow valve stem to control the flow of fuel thereinto and into the device.

12. In a device of the class described a fuel supply chamber, a dash pot chamber 90 communicating therewith, an outlet chamber, a mixing chamber, a double automatically acting valve mounted to control the flow through said mixing chamber and into said outlet chamber, a fuel supply valve 95 adapted to feed fuel into said mixing chamber and connected for operation with said automatic valve, and means on said fuel valve to cause an augmentation of pressure in the fuel supply valve with movement of 100 said automatic valve to spray the hydro-carbon fuel under pressure into the mixing chamber.

13. In a device of the class described a carbureter having a throttle valve, a fuel 105 supply valve, and a unitary double hollow valve member, said member by movement serving to open the fuel supply valve to admit fuel into the interior of said hollow valve member. 110

14. In a carbureter of the class described a plurality of fuel supply means disposed at different points and at different levels, a hollow valve member, and means associated therewith acting when said valve member is 115 operated to introduce fuel under pressure to said different supply means.

15. In a device of the class described a mixing chamber, a float feed chamber, a dash pot connected with said float feed 120 chamber, a double automatically acting valve controlling the inlet and outlet from said mixing chamber, a fuel supply valve connected for operation by said automatic valve, an auxiliary fuel supply chamber 125 connected with said dash pot, a nozzle secured in said auxiliary chamber and projecting into said mixing chamber, and means secured on said first mentioned fuel valve for forcing hydro-carbon fuel there- 130

through and through said nozzle under pressure greater than atmospheric with an opening of said automatic valve.

16. In a carbureter a double valve member mounted in the mixing chamber, a fuel valve projecting into said mixing chamber and connected for operation by said first mentioned valve, and means connected to said double valve member, to cause a jet 10 of fuel under pressure to flow through said fuel valve with an initial opening of said valve member.

17. In a device of the class described a float feed chamber, a mixing chamber, a 15 dash pot in communication with said float feed chamber, a fuel valve, a piston on said fuel valve in said dash pot chamber, and a double valve member adapted to move said fuel valve element to cause said piston to 20 force fuel therethrough under pressure to said mixing chamber.

18. In a device of the class described, a double automatically acting valve member, a fuel supply valve, and means introducing 25 fuel through said fuel supply valve in excess of that withdrawn by aspiration when said automatic valve is actuated.

19. In a carbureter of the class described a hollow valve, fuel inlet means therewithin, fuel inlet means adjacent said valve, and mechanism operating to force fuel under 30 pressure through said respective fuel inlet means.

20. In a device of the class described, a 35 hollow draft operated double valve member, fuel inlet means disposed therewithin and movable therewith, and mechanism operated by said valve member to force fuel through said inlet means under pressure into 40 the interior of said valve member.

21. In a device of the class described a hollow draft operated valve, inlet fuel means disposed therewithin and movable therewith, stationary fuel inlet means, and 45 mechanism operated by said valve to force fuel under pressure through said respective fuel inlet means.

22. In a device of the class described a mixing chamber having inlets and an outlet therefrom, a double valve member controlling said outlet and one of said inlets of 50 said mixing chamber, another valve controlling another of said inlets to said mixing chamber, and means introducing fuel for carburetion of the air into said mixing chamber.

23. In a carbureter of the class described the combination of a mixing chamber, an inlet chamber therefor, an outlet chamber 60 communicating with said mixing chamber, a valve member mounted beneath said mixing chamber controlling the respective passages of communication between the inlet and outlet chambers of the carbureter with 65 said mixing chamber, a plurality of fuel in-

let means, and mechanism operated by said valve member to introduce fuel under pressure through said respective fuel inlets.

24. In a carbureter having an air inlet and a throttle controlled mixture outlet, suction 70 operated means for varying the area of said air inlet, two fuel inlets, one of said fuel inlets being permanently open, means controlled by said suction operated means for varying the discharge capacity of the 75 other of said fuel inlets, and a liquid dash pot for retarding the movements of said suction operated means.

25. In a carbureter, a carbureting chamber, an air inlet, a fuel inlet of fixed capacity, suction operated means for varying the area of said air inlet, a dash pot supplied with liquid fuel, a tubular member communicating the movements of said suction operated means to the piston of said dash pot, a fuel valve in said tubular member, means for varying the capacity of said fuel valve by the movements of said tubular member, an orifice in the side of said tubular member for discharging fuel into said carbureting chamber, and manually operated means for adjusting said fuel valve. 80 85 90

26. In a carbureter, two air inlets, a fuel inlet for each of the air inlets disposed in the path of air entering its respective air 95 inlet, a suction operated valve for one of said air inlets, a stem for said valve, a fuel conduit in said stem, and means for retarding the movement of said valve.

27. In a carbureter, two air inlets, a fuel 100 inlet disposed in the path of air entering each air inlet, suction operated means for varying the area of one of said air inlets, means rigidly attached thereto for varying the discharge capacity of the fuel inlet associated therewith, and means for retarding the movement of said suction operated means. 105

28. In a carbureter, two air inlets, two fuel inlets at different points within the carbureter, suction operated means for varying the area of one of said air inlets, a cylinder supplied with liquid fuel, a piston in said cylinder, a tubular member communicating the movements of said suction operated 110 means to said piston, a fuel valve in said tubular member, means for varying the capacity of said fuel valve by the movements of said tubular member, and manually operated means for adjusting said fuel valve. 115 120

29. In a carbureter, two air inlets, a fuel inlet for each of the air inlets disposed in the path of air entering its respective air inlet, a suction operated valve for one of said air inlets, a stem for said valve, a fuel 125 conduit in said stem, and means for retarding the movement of said valve.

30. In a carbureter, the combination of a mixing chamber, a valve for regulating the draft through the mixing chamber, float 130

feed means for providing a normal supply of fuel to the mixing chamber, and means for injecting fuel in excess of the normal supply into the mixing chamber comprising 5 a fuel chamber, a member actuated by the opening of the aforesaid valve to apply pressure to the fuel in the fuel chamber, and a stem connected with the said member and provided with a passageway therein having 10 an outlet therefrom into the mixing chamber for conducting fuel under pressure into the mixing chamber.

31. In a carbureter, the combination of a mixing chamber, a valve for regulating the 15 draft through the mixing chamber, float feed means for providing a normal supply of fuel to the mixing chamber, a fuel reservoir, and a pump connected with said valve and adapted simultaneously to withdraw 20 fuel from the reservoir and expel fuel to the mixing chamber to augment the normal supply of fuel as the valve is opened.

32. In a carbureter the combination of a casing having a mixing chamber, a valve 25 controlling the air inlet to the mixing chamber, a nozzle for discharging fuel into said chamber, means controlled by the movement of said air inlet valve for varying the discharge of fuel, and means for temporarily increasing the discharge of fuel through 30 the nozzle independent of the position of the air valve.

33. In a carbureter the combination with a casing containing the mixing chamber, of 35 a valve controlling the air inlet to said chamber, a nozzle for discharging the liquid fuel into said chamber, means for

varying the flow of the liquid fuel with each change in position of the air valve, and means for additionally increasing the flow 40 of the oil upon a sudden opening of said air valve and for restoring the normal flow upon the cessation of said sudden movement.

34. In a carbureter, the combination with 45 a mixing chamber and an automatic valve for controlling the air inlet thereto, of a passage connecting with said mixing chamber through which air is normally drawn, a dash-pot for retarding movement of said 50 automatic valve, and means utilizing the pressure in said dash-pot for raising the level of the oil to said air passage, whereby auxiliary oil is discharged in the mixing chamber. 55

35. In a carbureter, the combination with a mixing chamber, of an automatic valve controlling air admission thereto, said valve having an oil passage opening into the mixing chamber, a chamber with which said 60 passage communicates, metering means controlling such communication, a piston in the second-named chamber connected with said automatic valve, a fixed means for by-passing oil into the mixing chamber under pressure 65 of said piston.

In testimony whereof I have hereunto subscribed my name in the presence of two subscribing witnesses:

CHARLES L. RAYFIELD.
